(57) **CLAIM**

The ornamental design for a set of wall mounts for exercise rack, as shown and described.

DESCRIPTION

FIG. 1 is a top, front, right perspective view of a set of wall mounts for exercise rack showing my design;

FIG. 2 is a top, front, left perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a bottom, front, right perspective view thereof.

The broken lines immediately adjacent to the shaded area are directed to boundary lines which form no part of the claimed design. The broken lines in the drawings are for the purpose of illustrating portions of the set of wall mounts for exercise rack and form no part of the claimed design.
